By Act.

UNITED STATES PATENT OFFICE.

CHARLES BREARLEY MOORE, OF EVANSTON, ILLINOIS, ASSIGNOR, BY MESNE ASSIGNMENTS, TO AMERICAN ARCH COMPANY, OF NEW YORK, N. Y., A CORPORATION OF NEW YORK.

REFRACTORY ARCH FOR LOCOMOTIVE-BOILER FURNACES.

1,109,692.

Specification of Letters Patent.

Patented Sept. 8, 1914.

Application filed November 17, 1908. Serial No. 463,070.

To all whom it may concern:

Be it known that I, CHARLES B. MOORE, a citizen of the United States, and resident of Evanston, Cook county, Illinois, have invented certain new and useful Improvements in Refractory Arches for Locomotive-Boiler Furnaces, of which the following is a full, true, clear, and exact description, such as will enable others skilled in the art 10 to make and use the same.

My invention relates to improvements in refractory arches for locomotive boiler furnaces and has special reference to improvements in arches of the kind which are carried by or are supported upon circulating tubes or so-called arch tubes within the firebox.

The object of my invention is to provide an improved refractory arch which shall 20 be composed of a plurality of refractory bricks each of a size to be inserted through the door of the furnace and which when placed in position shall be adapted to interlock in such manner as to form a substantially solid refractory body upon the supporting tubes.

My invention will be more readily understood by reference to the accompanying drawings forming a part of this specification and in which;

Figure 1 is a vertical longitudinal section of a locomotive fire-box containing an arch embodying my invention, the section being on the line Y—Y of Fig. 2; Fig. 2 is a horizontal sectional view on the line X—X of Fig. 1; Fig. 3 is an enlarged vertical transverse section on the line Z—Z of Figs. 1 and 2; Fig. 4 is a similar view illustrating the form of the arch in a "narrow" firebox; 40 and Figs. 5 and 6 are perspective details of the ends of two of the arch bricks showing how they are formed to interlock.

A locomotive fire-box as shown in the drawings is arranged within the shell, 2, of the boiler; it is made up of the flue sheet, 3, the rear end sheet, 4, the side sheets, 5—5, and the crown sheet, 6. The flues, 7, lead forward from the flue sheet, 3; the rear sheet contains the fuel door opening, 8. 10 represents the grate. A plurality or group of arch tubes, 11, extend from the lower part of the flue sheet to the upper part of the rear sheet. The refractory arch, A, about to be described rests upon and is sup-

ported by these arch tubes, 11. The lower 55 end of the arch preferably abuts the flue sheet, 3. In a fire-box of the wide type there are usually four of the water circulating or arch tubes, 11, and the arch is made up of three longitudinal rows of refractory bricks. 60 In Fig. 2 the bricks composing the several rows are marked, A', A², and A³. Each brick is of a size which will permit its being introduced into the fire-box through the fuel door, 8. Smaller bricks are not desirable 65 nor are larger bricks. All of the bricks are long enough to reach across two of the tubes, 11, and the ends of the brick are shaped or formed to interlock upon lines above said tubes. Thus as shown in Figs. 2 and 3 the 70 ends of each brick are inclined and provided with locking ribs or ledges, A⁴, and grooves, A⁵. The bricks, A' and A², are relatively inverted and the ribs or ledges of each brick fit the grooves of the adjoining bricks. I 75 prefer that abrupt angles shall be avoided, hence the beveled or inclined ends or surfaces, A⁶, A⁶, upon the bricks. By interlocking the bricks of each transverse row in this manner I enjoin or organize them into 80 a body of sufficient weight to retain its place upon the tubes, 11. As the bricks occupy inclined positions upon the tubes, it is not necessary to interlock them upon transverse lines. A "narrow" firebox as shown in Fig. 85 4 usually contains only three arch tubes, 11', 11', 11', and in these cases I form the arch of only two longitudinal rows of bricks, b', b'. The ends of the bricks abut above the middle tube, 11', and are interlocked by 90 ledges, A⁴, A⁴, of the same general form as before described. The outer ends, b'', of the bricks need not be provided with interlocking ribs and grooves, but are preferably beveled as shown in Fig. 4. The advantage 95 of the particular brick form herein shown is that the bricks are interchangeable.

As the various modifications of my invention will readily suggest themselves to one skilled in the art, I do not confine the invention to the specific structures herein shown and described.

Having thus described my invention, I claim as new and desire to secure by Letters Patent:

1. A refractory arch brick of greater length than width having its ends reversely inclined and having each end thereof pro-

- vided with a longitudinal rib and a complementary groove parallel therewith and adapted to receive the complementary rib of a like brick, said ribs and grooves being co-extensive with said ends of the brick.
2. A locomotive boiler furnace containing a plurality of arch tubes in combination with a substantially flat refractory arch thereon composed of a plurality of rows of bricks resting upon said arch tubes and having abutting ends above respective tubes, each of said bricks having a complementary interlocking rib and recess on each of its ends, the ribs of adjacent bricks entering respectively the recesses thereof and preventing the endwise separation of the bricks upon said tubes and permitting the free removal of certain of said bricks, as and for the purpose specified.
3. A refractory arch for locomotive boiler furnaces composed of substantially identical bricks, wedge-shaped at their ends and provided thereon with complementary hooked interlocking parts which prevent relative endwise separation of any two abutting bricks, the alternate bricks being reversed whereby certain thereof may be freely raised out of the arch for repairs.
4. A substantially flat refractory arch for locomotive furnaces composed of relatively reversed wedge-shaped bricks having complementary interlocking ribs and grooves upon their abutting wedging surfaces laterally coextensive therewith whereby the interlocked bricks are retained in abutting relation in the plane of the arch, but are free to be separated vertically.
5. A substantially flat refractory arch for locomotive boiler furnaces comprising a plu-

rality of longitudinal substantially identical rows of refractory bricks, the bricks being also arranged in transverse rows, each of said bricks being reversely beveled at its ends and having a rib and groove along each end to interlock with the corresponding rib and groove in an abutting brick, the said bricks when interlocked preventing transverse separation of bricks and permitting free vertical removal of certain of the bricks.

6. A locomotive boiler firebox, in combination with a group of four substantially parallel, inclined arch tubes arranged longitudinally therein, a refractory front arch supported on said tubes and in contact with the flue sheet said arch consisting of a plurality of transverse rows of substantially identical bricks, each brick having oppositely beveled ends provided with complementary ribs and grooves and adapted when adjacent bricks are reversed in position to interlock the bricks against transverse separation, each of said rows consisting of three bricks, the outer two thereof being arranged with their longer sides resting upon two tubes, the center brick being reversed in position with its shorter side turned downwardly, supported by and filling the space between said two outer bricks, whereby said middle brick is removable from its position without disturbing the end bricks.

In testimony whereof, I have hereunto set my hand, this 2d day of November, 1908, in the presence of two subscribing witnesses.

CHARLES BREARLEY MOORE.
